UNITED STATES PATENT OFFICE.

JOHN J. CARTY, OF CAMBRIDGE, ASSIGNOR TO THE AMERICAN BELL TELEPHONE COMPANY, OF BOSTON, MASSACHUSETTS.

TELEPHONE SIGNALING APPARATUS.

SPECIFICATION forming part of Letters Patent No. 288,691, dated November 20, 1883.

Application filed October 4, 1883. (No model.)

To all whom it may concern:

Be it known that I, JOHN J. CARTY, of Cambridge, in the county of Middlesex and State of Massachusetts, have invented certain Improvements in Telephone Signaling Apparatus, of which the following is a specification.

My invention relates to electric-signal bells, such as are used in connection with telephones for signaling between stations. It has particular reference to an improved combination of the cut-out or short-circuiter with the working parts of the said bells.

In the ordinary magneto-telephone bell it is usual to combine a through-circuit for the signal-bell magnet, a branch circuit of the same through the generating-helix, this latter being normally shunted by a short wire, the said shunt being adapted to be broken when the generator is operated either by a manual circuit-breaker or by an automatic device attached to the generator-crank. A second circuit, whereby the line is directed through the telephones, is also incorporated in the bell mechanism and adapted to be included in the main line when the telephone is removed from its support. It has been common in telephone-station apparatus of the foregoing character to provide a lightning-arrester, consisting of a pair of metallic plates, one connected with the wire leading into the bell, and one with the wire leading out of the bell. A ground-plate is placed in near proximity to these line-plates, and both have serrated edges, to the end that in case the wires are heavily charged with atmospheric electricity, the said electricity will leap from the line to the ground-plates, leaving the instrument-coils uninjured. These plates are also perforated at their edges, which approximate to one another, so that a metal plug may be inserted in the hole thus formed to unite them electrically. When a plug is so inserted it forms practically a cut-out or short-circuit round the entire bell. Persons having the charge of the telephone are instructed to insert the plug on the approach of a lightning storm, so that the bell coils may be protected from injury. In the use of this device it has been found, in practice, that after the plug has been inserted to

short-circuit the bell, the person accustomed to use the telephone, through forgetfulness or negligence, omits to withdraw the same upon discontinuance of the storm, and thus the bell is rendered useless, and cannot be utilized either for sending or receiving call-signals, until the fact that the cut-out plug is inserted is discovered, and the plug withdrawn. The telephone connected with the apparatus is from the same reason inoperative.

The object of this invention is to prevent this omission; and to this end the invention consists in placing the cut-out plug and lightning-arrester in such relation to the operating-crank of the generator that if the said plug is in position to short-circuit the bell, it also forms a mechanical obstacle to the revolution of the crank, so that the crank cannot be turned until it be withdrawn.

Heretofore it has been the uniform practice to place the lightning-arrester and its concomitants on the top of the bell, a position in most cases above the range of vision of the operator, and not at all adapted to attract the notice of the operator. In this invention I place it on the side or front of the bell, within the radius of the operating-crank, so that its position will at once be noted by an intending operator; or, in the event it is not noticed, it will be brought to the attention of said operator by the concussion of the crank with the short-circuiting plug before the completion of the first revolution.

The accompanying drawings illustrate the manner in which the principle of my invention is carried into effect.

Figure 1 is a side elevation of a magneto call-bell with the cut-out plug inserted and the crank in its normal position. Fig. 2 is a diagrammatic view of the several circuits; and Fig. 3 is a detail showing the position of the crank when an attempt is made to operate the generator while the cut-out plug remains inserted.

In Fig. 1, A is the bell-box, B the crank by which the generating-armature is rotated, and C the short-circuiting plug inserted between the lightning-arrester plates a and a', which are placed on the side of the box in immediate

proximity to the ground-plate *b*. I will now describe the diagram in Fig. 2, by which the efficiency of my device will be made apparent.

The main-line wire 1, entering the instrument, is attached to the cut-out plate *a*, from thence it passes by wire 3 to the call-bell magnet *D*, and thence by wire 4 to the switch-hook *f*. When the telephone is in place on the hook, the circuit is continued through the spring *e*, wire 6, springs *i* and *j*, and wire 8 to the opposite lightning-arrester plate *a'*, to which is attached the outgoing line 2. A branch-circuit is led from the wire 6 to the wire 8, by means of the spring *g*, generating-armature *E*, spring *h*, and wire 7; but this circuit, with the generator *E*, is normally short-circuited by the springs *i* and *j* with the connecting wires, but may be made a part of the main circuit by pressing the button *K*, and thus separating the springs *i* and *j*. When the telephone is taken from the hook, the said hook flies up and makes contact with the spring *d*, at the same time breaking the original contact with the spring *e*. The circuit then continues from the wire 4 to the spring *d*, wire 5, telephone *T*, and transmitter *T'*, wire 9, and plate *a'* to the out-wire 2. The ground-plate *b* is, as shown, connected with the ground *G*. Between the lightning-arrester plates *a* and *a'* is a hole, *c*, wherein a cut-out plug, *C*, may be placed. When a plug is so placed, the entire arrangement of circuits and electro-magnets within the bell-box is short-circuited, the line-circuit passing from the line-wire 1 to plate *a*; thence by plug *C* to plate *a'*, and to the outgoing line 2. In practice, these plates are placed upon the side of the box, as in Fig.

1; and the only object in showing the circuit arrangement, as in Fig. 2, is that the function of the said plates and their plug may be apparent. When thus placed, while the plug is in, it projects outwardly from the side or front of the bell-box, as shown in Fig. 3, in which *A* is a part of the box, *a* the cut-out plate, *b* the ground-plate, and *C* the inserted plug. *B* is the operating-crank. The crank is placed, as shown, close to the lightning-arrester, so that if the plug *C* be inserted any attempt to turn the crank will be fruitless, because it will strike the plug, as shown in Fig. 3. It is self-evident, then, that in the event of such an impingement, the position of the cut-out plug will be forcibly brought to the notice of the operator, who may at once remove the same.

What I claim as my invention, and desire to secure by Letters Patent of the United States, is—

The combination, with the operating-crank of a magneto-electric call-bell, of the lightning-arrester plates and short-circuiting plug so placed with reference to the said crank that when the plug is inserted between the said plates, short-circuiting the bell, it forms a mechanical obstacle to the revolution of the crank, substantially as described.

In testimony whereof I have signed my name to this specification, in the presence of two subscribing witnesses, this 2d day of October, 1883.

JOHN J. CARTY.
